METHOD OF AND MACHINE FOR REGISTERING AND PROVING PLATES

Henry A. Wise Wood, New York, N. Y., assignor to Wood Newspaper Machinery Corporation, New York, N. Y., a corporation of Virginia

Application May 5, 1931, Serial No. 535,165
Renewed August 18, 1936

34 Claims. (Cl. 101—174)

This invention relates to the printing of newspapers, or the like, in which the product is produced in a plurality of colors.

It will be obvious that where a number of cylinders are used, each having plates of a different color from the plates on the other cylinders and these are all used to form imprints on the same page, the printing plates on the different cylinders must register properly with each other. Heretofore it has been necessary, after the plates have been put on the press cylinder, to shift the plates about to obtain the proper register of the final product. This is a tedious and time-taking task and involves the printing of many proofs to see that the plates are finally in proper register.

This invention relates to a method and apparatus by which the plates are pre-registered and proved in a very simple manner and then easily and accurately placed on the printing cylinders in a position in which they will all register properly with each other, thus eliminating the necessity of shifting the plates after they are put on the printing cylinders and while the whole press is idle.

The principal objects of this invention are to provide for the registering of printing plates by providing the plate cylinders of the printing press with fixed locating means for the plates, such as pins projecting therefrom, and before the plates are placed thereon, proving them on another machine by comparing their imprints with those of a key-plate which is placed on a cylinder and kept there in the same position, and when the other plates are brought to proper register with the key-plate, marking them, as for example, with notches in their edges to be brought into engagement with the said pins when the plates are placed on the printing cylinder; to provide a proving and registering machine involving an impression cylinder located between a proving cylinder and a marking cylinder and adapted to run in cooperation with either or both, whereby the key-plate can be placed on the proving cylinder and impressions made on the impression cylinder from the key-plate, and the plate being registered until these impressions coincide so that at that time the plate being tested can be marked or notched to show its correct position on the printing plate cylinder to which it is to be applied afterwards; to provide the proving cylinder with inking means which can be withdrawn from engagement with it very easily and brought into contact with it with the same ease; to provide means for moving the proving cylinder and the marking cylinder independently into and out of contact with the impression cylinder in a very simple way; to provide a plurality of inking devices for different colors of ink cooperating with the marking cylinder, and each one having an ink transferring roll readily movable into and out of contact with the marking

cylinder; to provide means connected with the marking cylinder for shifting the plate, which is to be tested, circumferentially and longitudinally on said cylinder to register it with the key-plate; to provide means for driving the impression cylinder and the marking and proving cylinders accurately from the same source of power; to provide improved means for locking up the plates on the marking cylinder so that they can be readily released for movement to get them into proper registration; to provide means of a simple and accurate character for making notches or marks in the edges of the plates on the marking cylinder; and to provide means for operating the plate clamps on the printing plate cylinder in proper relation to the locating pins thereon and having means by which they can be quickly clamped and released.

Other objects and advantages of the invention will appear hereinafter.

Reference is to be had to the accompanying drawings, in which

Fig. 1 is a side view of a preferred form of the driving mechanism of the proving and registering machine;

Fig. 2 is a side view of the marking cylinder and the inking mechanisms therefor;

19 Fig. 22 is a side view of one of the plate locking cams used in this form of the device, and

20 Fig. 23 is a view of the printing plate itself with the notches therein for locating it on the printing plate cylinder.

25 This invention is particularly applicable to newspaper color printing and is extremely useful where more than one set of color plates is used. The principal registering means as set forth herein may be applied to color plates that are manufactured by the electrotype process but it is designed particularly, and is especially advantageous, for stereotype plates, as each similar plate carries its characters in definite relationship to the bevels on the sides of the plate and 30 the margins on the ends of the plate.

35 According to this invention, the plates are pre-registered by placing a key-plate, say a black plate, in the registering machine, which is the subject of part of this invention, and setting it into approximately the desired position. Notches are cut in the edges of this plate, or the edges are marked, and it is transferred to a proving cylinder which is a part of the registering machine. On this machine is an impression cylinder 40 and a marking or notching cylinder besides the proving cylinder. The proving and marking cylinders are adapted to be inked and they are adapted also to be moved into contact with the impression cylinder which has a blanket as usual. The proving and marking cylinders are of the 45 same size as the printing plate cylinder of the printing machine on which these plates are to be used for printing and the impression cylinder is of twice that diameter.

50 The plates that are to be proved and registered, whether they are to be inked with black or other colored ink, are successively placed on this marking cylinder where impressions are made from them and impressions made from the key-plate on the same sheet so that these 55 impressions can be checked with respect to each other. Then the plate to be proved is adjusted on the marking cylinder until its imprint registers with the black of the key-plate on the proving cylinder. When they have been adjusted so 60 that the registration is perfect, they are marked or notched on this marking cylinder.

65 In the preferred construction, notches are made on these plates in their curved edges and registering pins are fixed on the press cylinder in a position so that each one of these plates that has been notched can be placed on the press cylinder with the pins in the notches. Then all 70 these plates of a series will be in exact registration with each other in the printing machine.

75 Therefore their imprints on the web by the printing machine will be in registration and there will be no overlapping of the colors and no blank spots unless such are provided for in the design. This eliminates the juggling of the plates

on the printing press cylinders and transfers that part of the usual operation to this registering machine where it is done at convenient times and does not delay the locating of the plates on the printing machine.

It will be seen therefore that if it is desired to 5 register a red plate, a trial sheet will be passed under the black plate on the proving cylinder and then under the plate to be registered on the marking cylinder. The operator observes the 10 result to see what must be done to make the red register with the black, which of course is fixed. Adjustments are made for moving the red plate circumferentially or longitudinally until the 15 proper register is obtained. Several proofs may be made before the red plate is in the proper registering position. It is at this time that the red plate is notched and removed.

The impression cylinder is provided with two 20 sets of grippers. On one set, a sheet is carried which is printed upon the front when the plates are in correct register so that when a final set 25 of plates has been notched, they can be put back on the notching cylinder one at a time and a complete proof carrying all the colors is obtainable on the registering machine. It will be obvious, therefore, that when these plates are transferred to the cylinders of the printing press and placed thereon with the pins of the plate cylinders 30 thereof in the notches of their respective plates, the printing will be the same as this complete proof that has been obtained previously.

The registering and proving machine is mounted 35 on a bed plate 10 which carries a frame-work involving a series of uprights 11, of course, in pairs on both sides of the base, to support all the machinery involved. The machine embodies a central impression cylinder 12, a marking cylinder 13 and a proving cylinder 14. As stated, the marking cylinder and proving cylinder are shown 40 as of the same diameter as the printing cylinder on which the printing plates are finally to be placed for printing. Thus the semi-cylindrical plates fit these cylinders in the same way as they do the printing plate cylinder. The impression cylinder is twice the diameter for the other two cylinders.

The machine is run by a motor 15 which, 45 through a worm 16 on its shaft, operates a gear 17 which is fixed with respect to the impression cylinder and mounted on the shaft 18 thereof and also is of the same diameter. At times, as will appear, a pair of gears 19 and 20 on the marking and proving cylinders mesh with this gear 17 to 50 drive these latter cylinders.

55 On the shaft 18 is shown a bevel gear 21 meshing with a bevel gear 22 on a vertical shaft 23 which, by bevel gears 24, drives a horizontal shaft 25 which extends throughout the length of the machine. On this shaft 25 are worms 26 which 60 drive the several inking mechanisms as will appear.

The gears 19 and 20 are adjustably secured to the cylinders 13 and 14 respectively. This adjustment is secured by bolts 27 screwed into the hubs 65 28 of these two cylinders. A back-lash plate 29 is provided adjustably secured to the gear 19 or 20 of such a nature that lost motion may be eliminated.

The marking cylinder and proving cylinder are 70 mounted in eccentric bearings 30 so that they may be moved into or out of contact with the impression cylinder. The mechanism comprises a turn-buckle 31 pivotally attached at one end to the eccentric bearing 30 and at the other to a 75

lever 32, which is oscillatably mounted on a shaft 33 carried by the frame-work. The shaft has a handle 34 for operating this mechanism. These turn-buckle and handle arrangements are placed on each end of the machine so that the two eccentric bearings of either shaft will move in unison to bring the desired cylinder into contact with the impression cylinder.

The proving cylinder is provided with a pair of locating pins 35 placed in fixed position longitudinally in alignment on the cylinder and having preferably V-shaped angular sides both pointing inwardly toward each other so as to receive thereon between them this plate having previously been notched or marked on the marking cylinder. A pair of plate clamps 36 are provided for holding the plate on the cylinder, as indicated in Fig. 13. The particular way of operating these plate clamps is not illustrated in detail because they can be moved toward each other after the plate is located on the pins and clamped in any usual or desired way. It will be understood that it is only half of the proving cylinder that is used, the other half not being employed, although of course the pins and clamps could be duplicated on the other half if desired but the two halves would not be used simultaneously.

The marking cylinder 13 is provided with means for holding and clamping the plate to be registered on a half of its circumference. It is provided with end plate clamps 37 and 38. The latter is pressed against the plate by a coil spring 39 and is withdrawn from the plate by a rod 40 having a head adapted to pull the clamp back. This rod is operated by a bell crank 41 having a roll 42 that is operated by a cam 43 on the hand lever 44. The plate clamp 37 cooperates with a screw 45 entering the clamp and having a hand wheel 46 for operating it. A spring-pressed ball 47 constitutes a detent for fitting in a depression in the clamp. This furnishes the operator with some guide by which the first notch or mark can be located on the key-plate in approximately central location. By manipulation of the hand wheel 46, the end clamp 37 is directly operated back and forth but it is used to press the plate on the cylinder in a direction away from this end. The plate is moved back by the spring 39 when the screw is turned in the opposite direction. This affords adjustment to bring the plate into proper longitudinal position. As stated, this operation may have to be performed several times to get the plate to be proved into registering position longitudinally.

For side register or circumferential adjustment, fingers 48 are provided on the cylinder 13 projecting outwardly in opposite directions into the path of the straight edges of the plate. They are mounted on studs 49 and arms 50 extend from them fixed with respect to the fingers 48 so that they swing together on the studs. The two arms 50 are connected by a cross link 51 which is provided with a notch 52 into which a bent spring 53 will settle when the parts are in the normal position. Thus when it is necessary to move the plates circumferentially a little to secure better register, this can be done by turning a hand wheel 54, which is provided with a pinion 55 meshing with a rack 56 on a link 51 which is secured to the end of the shaft 49. Of course two of these are provided, one on each side of the cylinder, and when motion of this kind is made, the cross link 51 will have to move in one direction or the other. This movement is resisted by the spring 53 so that the motion is made against spring pressure. The

notch is provided in the cross link 51 at the proper place so that when the first plate is put on, it will be substantially in central position.

The proper procedure is to turn the hand wheel 54 until the notch and spring coincide so that certain of the registering operations will occur at a substantially central location. Of course to move the plate circumferentially, the end clamps have to be loosened up either by turning the hand wheel 46 or employing the lever 44 for that purpose. In this way it will be seen that for the process of trial and error in moving the plate to the proper position, simple adjustments are provided for moving the plate both circumferentially and longitudinally until accurate register is obtained.

When the plate on the cylinder 13 is properly adjusted and its imprint registers perfectly with the imprint on the black or key-plate on the proving cylinder, the plate being registered is marked or notched. This is accomplished by mechanism operated by a hand lever 59 which is connected by a link 60 with a cam 61 so as to move it from the full line to the dotted line position in Fig. 6. This cam is not rotary but is mounted on studs 62 which pass through the frame. These studs are surrounded by springs 63 which normally hold the cam back in the full line position in Fig. 6. When it is moved over into the dotted line position, it is interposed in the path of a cam roller 64. This cam roller is on an arm 65 fixed on a shaft 66 carried by the cylinder 13 and pivotally connected with it by arms 67 are two marking or notching chisels 68. The two chisels are arranged the same at both ends. Therefore, when the lever 59 is operated, at the proper time during the rotation of the shaft of the cylinder 13 the plate held thereon will be notched in its opposite curved edges. These notches are triangular, one as shown at 69 on the completed plate P in Fig. 23. These chisels or equivalent means may merely make a mark which can be used to register the plates against marks or pins on the printing plate cylinder.

The first plate or key-plate which is notched in this way is transferred to the proving cylinder and these notches are located on that cylinder by means of the pins 35 thereon. This plate is left on the proving cylinder as long as the job lasts and thereafter the plates notched on the notching and marking cylinder are removed therefrom and placed on the printing plate cylinder which then come against locating pins 70 and 71 on this cylinder. The pin 71 is double-ended so as to provide for locating two plates P and P' on opposite sides. Instead of these pins, marks can be made on the printing plate cylinder and the marked color plates put on in registration with them and clamped in that position. However, the notches and pins definitely locate them and hold them while the plates are being clamped. Therefore the notching is preferred.

The impression cylinder 12 carries two of the usual press blankets. One end of each blanket is placed over a row of pins 73 and the other end of each blanket is wound up on a blanket tightener rod 74. Each blanket extends around a quarter of the impression cylinder and therefore each one may register with a plate extending around half of the marking cylinder or proving cylinder. The other two quarters of the impression cylinder are without a blanket.

The well known gripper for holding the sheet on the impression cylinder is shown. As this is well known it requires no particular description.

but briefly, a gripper finger 76 mounted on a shaft 77 also carries secured to it a cam 78. The gripper is held in place by a rod 79 pivotally attached to the cam 78 and pressed by a spring 80 abutting against a poppet 81, fixed on the end of the cylinder. Jam nuts 82 provide adjustment and limit the motion of the gripper. Two such gripper arrangements are provided because the impression cylinder is arranged to print on two sheets on opposite quadrants. Small perforating pins 84 are provided for holding down the tail end of the sheet.

The operation of the gripper is accomplished in a well known manner by a lever 85 pivotally mounted on a projection 86 above the bearing of the cylinder 12. The lever 85 is pivotally attached to operating pins 87 so that oscillation of this lever causes one of these pins to project into the path of the cam 78 and the other to be withdrawn. The projecting pin operates the gripper cam 78 as usual.

By this means the rotation of the cylinder 12 rotates the gripper cam and its shaft in a counterclockwise direction to open the gripper when actuated by one of the pins 87 and in a clockwise direction to close the gripper at the proper time by the other pin 87. When the lever 85 is placed in a neutral position, neither pin operates. Then the sheet is carried around on the cylinder 30 as desired or the cylinder can be rotated without any sheet.

A well known type of table 90 and feeding arrangement is shown with a paper stop 91. It will be understood that at the time the gripper 35 is made to operate to pick up a sheet, the feeding arrangement that has positioned the sheet releases it so that it will be carried around the impression cylinder.

In accordance with what has been said it will 40 be obvious that after each plate is properly adjusted on the marking cylinder, means will be provided thereon for making the marks or notches that have been mentioned in the edges of the plate. For this purpose the cam 61 is operated 45 from the full line position in Fig. 6 to the dotted line position and held that way by the handle 52 until the cylinder 13 has made a complete revolution or enough of a revolution to perform the desired functions. This interposes the cam 50 61 in the path of a cam roller 64. The continued rotation of the cylinder 13 causes this cam roller to ride up on the cam, moving the arm 63 and turning the shaft 65 on which this arm is located. On this shaft also are a pair of 55 dial arms 95 which pivotally carry a pair of chisels 96. The rocking of the shaft 65 will thrust these chisels radially outward and, in the preferred form, they cut V-shaped notches in the opposite curved beveled edges of the plate. If 60 desired, the chisels can be formed merely to make a registering mark at this point.

Another arrangement for making the V-shaped notches or marks is shown in Fig. 10. This involves a pair of racks 97 mounted on a reciprocating bar 98, one of the racks 97 operating directly a segment 99 which is mounted on a shaft and carries a cutter 100. On the opposite end the corresponding segment 99 and cutter 100 are shown and operated from the other 70 rack 97 through an intermediate gear 101. The motion of this bar 98 to the left drives both cutters through the opposite curved beveled edges of the plate. This motion can be accomplished by a cam, not shown, or in any other 75 desired way.

As previously stated the marking or notching cylinder and proving cylinder are provided with printing plates and these plates are inked. For that purpose one inking mechanism is provided for the proving cylinder and a plurality of inking mechanisms for the marking cylinder, one for each color of ink to be used thereon so that the plates, after being proved, will not have to be cleaned before being used on the printing press. Each of these inking mechanisms is shown like the others and only one of them need be described. Each one involves an ink fountain 103, having a pivot 104 by which the fountain back 105 is pivoted thereon. Each one, of course, carries a fountain blade 105 which is provided with springs 106 forcing it toward the fountain roll 107. The proper adjustment of the fountain blade 105 to allow the desired amount of ink to pass up between it and the fountain roll is regulated by a hand wheel 108. To this wheel 10 is secured a worm 109 meshing with a worm wheel 110 secured to a shaft 111 rotatably mounted in the fountain back 105. Of course, there are two such worm wheels positioned essentially at each end of the fountain blade and meshing with the rack teeth 112 in the fountain blade so that 15 to-and-fro motion may be provided.

A wing bolt 113 is provided for holding the fountain back secured against the fountain. When it is desired to clean out the fountain or 20 any obstruction from beneath its blade, the movement of this wing bolt allows the blade 105 to swing around its supporting studs 104.

From the fountain roll 107 the ink, of course, 25 passes in the usual way to a pick-up roll 114. The fountain roll is driven from one of the worms 26 through a worm wheel 115 which is directly on a shaft 116. The connection of the fountain roll shaft with the shaft 116 which drives it is made through a tongue and slot connection 121 so that the shaft 116 can be drawn 30 out for repairs without taking the fountain roll out of its bearings. The pick-up roll is mounted on a shaft 117 and is driven from the main cylinder 13 or 14 through gears 19 and 20 meshing 35 with an idler 119 rotatably carried on a stud 120. This idler meshes with a gear 122 secured to the end of the pick-up roll shaft.

The pick-up roll shaft 117 is mounted in adjustable eccentric bushings 125 carried by the 40 machine frame. The outside ends of these bearings carry teeth 126 meshing with adjustable worms 127. Each adjustable worm is keyed to an adjusting stud 128 mounted on the frame and locked in position by a jam nut 129. The 45 rotation of the stud 128 through its square end, rotates the eccentric pick-up roll bushings to adjust the setting of the pick-up roll in its relation to the fountain roll.

On the frames carrying the fountain is pivotally mounted a frame 130 made up of two arms which carry the form roll 131 in split bearings 132 fixed in position by thumb-screws and nuts 133 as usual. Rotatably mounted on the pick-up roll bushing 125 is an eccentric bushing 134 which, through an adjusting worm 135 and its stud 136, may be rotated so that the form roll 131 will be adjusted to and from the pick-up roll 114. A lock nut 137 is provided so that when 50 the setting is properly made, the eccentric bushing 134 is locked and it oscillates as a unit with the arm or frame 130. This permits of the putting of the form roll into or out of engagement with the pick-up roll at all angular pos- 55 70 75 76

tions, as it rotates about its axis toward and from the plate cylinder.

The form roll 131 is pressed into contact with the plate through a spring 140 lying against a fixed lug 141 on the frame. The spring 140 is carried on a link 142 which is pivotally attached to the form roll frame 130 at one end and enclosing the eccentric strap 143 at the other end. A nut 144 acts as a stop, limiting the upward motion of the form roller, and also provides for adjustment for the proper contact of the form roll with the plate. The eccentric strap 143 surrounds an eccentric 145 which is secured to a cross shaft 146 mounted on the frame. An arm 147 is secured to the shaft 146 and is connected by a link 148 with a foot lever 149. This foot lever is provided with two treadles 150 on opposite sides of the pivot on which the lever is pivoted.

When the operator presses on the right hand treadle 150 the eccentric 145 is rotated in such a way that the form roll 131 is pulled against the pressure of the spring 140, out of contact with the plate. This eccentric is so arranged that it locks the form roll mechanism in this position by passing over the dead center. However, when it is desired to put the form roll 131 into contact with the plate, the operator presses on the left hand treadle 150, thereby rotating the eccentric 145 in the opposite direction. Thus the spring 140 is allowed and assisted to push the form roll 131 against the plate. A slot and stud connection 151 is used between the link 142 and the strap 143 to insure that the adjustment of the form roll will be controlled by the nut 144. This description applies to the inking mechanism for the proving cylinder and to the several inking mechanisms for the marking or notching cylinder.

As has been stated, the shaft 25 extending longitudinally through the machine drives the several fountain rolls through its worms 26. The bearings for the fountain rolls are constructed as is now usual so that they bear against the ends of the fountain rolls. Ink is prevented from being delivered up on the fountain rolls except at their peripheries and is prevented from working out of the fountain through the fountain roll bearings in this way. On the right hand 50 a seal 152 is secured to doubly insure the confinement of the ink.

At this point it may be stated that the mechanism so far described constitutes the entire machine for registering and proving the plates, and the plates one after another are taken off the marking or notching cylinder with the desired colored ink upon them ready to be transferred to the printing press. It will be seen that these plates can be in the process of being prepared, while the printing press is running, and no time has to be taken out for the registering of the plates and only very little for placing them on the printing plate cylinders.

Figs. 16 to 22 inclusive show several ways in which the plates may be secured on the printing plate cylinders, on which they are to be used, with their notches 69 in registration with the pins 70 and 71 thereon. Of course, it will be obvious that the plates may be clamped on the printing plate cylinders in any desired way and, in fact, in some of the ways that are in common use. However, I have shown in Figs. 16 and 17 one way in which the plates may be clamped, it being understood that they are registered almost instantaneously by the notches and pins.

In these figures a plate cylinder 154 is shown carrying an end piece 155 secured to it. In the end piece is mounted a short shaft 156 having a square 157 on the end for operating it and having a cam 158 pinned to it on the inner end. Cooperating with the cam 158 is a cam 159 pinned to a rod 160. This rod 160 passes into a chamber under the plate to be put on the cylinder and to its end is pivotally attached a pivoted arm 161. The turning of the shaft 156 moves the rod 160 to the right in these figures and therefore swings this arm 161. To this arm is in turn secured a short shaft 162. This shaft also is pivotally mounted in a stationary holder 163 secured to the cylinder. The shaft 162 has secured to it a gear 164 meshing with rack teeth 165 and 166 on two operating rods 167 and 168. These operating rods extend in opposite directions from the shaft 162 and their racks are arranged to engage opposite sides of the gear 164. They are pivotally attached to a pair of oscillating clamp levers 169 and 170 respectively. These clamp levers are held under spring pressure against the opposite bevel edges of the plate P through a pair of operating springs 171 and 172 and collars 173 on the rods 167 and 168. An additional extension arm 174 is pivotally attached to one end of the arm 161 and the other end is pivotally attached to a clamp lever 175. The clamp lever 175 is held under spring pressure against the beveled edge of an inside plate P' by a mechanism similar to that described above.

It will be seen that the motion of the rod 160 to the right operates to release all of the plate-holding mechanism used on the two plates on that end of the press plate cylinder. Of course, the inner side of the plate P' is held by a center clip 176 and spring 177 and all this mechanism is repeated on the other end of the cylinder.

In this way it will be seen that the inside plate may be angled underneath the center clip 176 and pressed over so that it drops down over the registering pins 71 and is thereby placed on the press in an easy manner which insures contact of the center clip and also insures a perfect registration of the plate.

It will be understood, of course, that as many of these mechanisms may be employed with a set of plate clamps for each one as may be found desirable. In Fig. 19 is shown an end clamp 180 and center clip 181 carried by T-slots of the usual construction in the cylinder. Both are held by the pressure of springs 182 against the beveled edges of the plate. Fixed on an operating rod 183 are cams 184 arranged oppositely. When this rod is rotated these cams cooperate with cam surfaces on the end clamp 180 and the center clip 181 and force these clips back in opposition to the pressure of their springs until they release the plate.

In Fig. 20 the rod 183 is shown as provided with a gear 185 and it is also provided with a square on its end. When this square is turned by a wrench, the gear operates two gears 186 rotatably mounted on studs 187 on the end of the cylinder. These gears in turn cooperate with pinions 188 to rotate two other operating rods 189 in all respects similar to the operating rod 183.

In Fig. 18 the three rods are shown and the center clips 181 are arranged in staggered relationship in order to provide sufficient room for moving each center clip without providing excessive room between the clips.

The center clips 181 are shown as pressing

against the inside plate while the two outer ones press against the inside bevel of the outside plate. In the middle arrangement the operating cam is placed in such a way that the clip is forced to the left when the plates are unlocked.

Each one of these cams 184, as shown in Fig. 22, is provided with a small flat space 190 at top of the cam path so that when the clips are fully open the wrench may be taken off the square end 10 of the central rod 183 and, on account of this flat space, there is no danger of the plates slipping into closed position on account of their springs.

A circular slot 191 is provided in one of the 15 intermediate gears 186 to cooperate with a pin 192 fixed in the cylinder to limit the motion of the whole gear train. This prevents the operating mechanism from being rotated past the proper stopping position.

20 The illustrations herein presented show the locking of only half a plate but the additional mechanism for locking the full plate with a single wrench could be provided in accordance with this invention.

25 It will be seen that the machine illustrated in the first fifteen figures provides means for registering the plates and proving them so that when the plates are to be put on the printing plate cylinder of the press, the press has to be stopped only a very short time and the entire 30 registering is accomplished outside the printing machine. Plates pre-registered and proved on the machine mentioned are almost instantaneously set on their printing plate cylinders absolutely in registering position.

Although I have illustrated and described a single form of the invention with only a few modifications thereof, I am aware of the fact that other modifications can be made therein by any 40 person skilled in the art without departing from the scope of the invention as expressed in the claims. Therefore I do not wish to be limited in this respect but what I do claim is:—

1. The method of registering printing plates to 45 be used on the plate cylinder of a printing press, which comprises preliminarily printing from a plate to be registered on impressions made from a key plate, shifting the plate to be registered until the impressions from the two plates register, marking the edges of the plate to be registered, and locating said plate on the plate cylinder of the printing press by said marks.

2. The method of registering and proving 50 curved printing plates to be used on the plate cylinder of a printing press, which comprises printing on a sheet from a key printing plate, printing on the same sheet from a plate to be registered and proved, shifting the second plate to bring it to a position in which its imprint will register with the imprint of the key plate, then notching the second plate and fixing it on the plate cylinder of the printing press with the notches in a definite predetermined position thereon.

3. The method of registering and proving 55 curved printing plates to be used on the plate cylinder of a printing press, which comprises printing a plurality of times from a key printing plate, printing on the same sheets from a plate to be registered and proved, shifting the second plate between impressions to bring it to a position in which its imprint will register with the imprint of the key plate, then notching the second plate and fixing it on the plate cylinder

of the printing press with the notches in registered position on the plate cylinder.

4. The method of registering and proving 5 printing plates, which consists in mounting a key plate on a cylinder, mounting the plates to be registered, one at a time, on a second cylinder, inking the plates, rotating the cylinders to provide an impression first from the first plate and then, on the same area, from the plate on the second cylinder, shifting the second plate 10 until the imprints from the two plates coincide, and then marking the plates, one after another on the second cylinder so that they can be put in definite positions on the plate cylinder of the printing press.

5. The method of registering and proving 15 printing plates, which consists in mounting a key plate on a cylinder of the same diameter as the plate cylinder of the printing press on which the plates are to be used, mounting the plates to be registered, one at a time, on a second cylinder of the same size, inking the plates with inks of different colors, rotating the cylinders to provide an impression first from the first plate and then, on the same area, from the plate on the second cylinder, and repeating that operation, shifting the second plate between impressions until the imprints from the two plates coincide, and then marking the plates, one after another on the second cylinder so that they can be put in 20 definite positions on the plate cylinder of the printing press.

6. In a machine for registering and proving 25 printing plates, the combination of means for supporting a key plate and a plate to be registered, and means whereby impressions can be made from both plates on the same surface, so that the impressions from the plates can be compared, with means for marking the second plate when it is in registering position, for assistance 30 in locating it on the plate cylinder of the press on which the plate is to be used.

7. In a machine for registering and proving 35 printing plates, the combination of means by which the imprints from two plates can be made 40 on the same sheet in order that one of said plates may be adjusted to bring the impressions of the two plates into exact registration, means for holding the plate being registered in that position, and means for marking that plate so that 45 it can be placed in a definite position on the printing plate cylinder.

8. In a machine for registering and proving 50 printing plates, the combination of an impression cylinder, a marking and a proving cylinder, both in printing contact with the impression cylinder, whereby imprints from two plates respectively on the marking and proving cylinders can be made on the same sheet on the impression cylinder in order that one of said plates may be 55 adjusted by manual means to bring the impressions of the two plates into exact registration, means for holding the plate being registered in that position, and means for marking that plate so that it can be placed in a definite position for the purpose described.

9. In a machine for registering and proving 60 printing plates to be inked with different colored inks, which plates are to be placed on cylinders of a printing press to print illustrations or the like in a plurality of colors, the combination of means for supporting one after another of the plates to be transferred to said press, means for supporting in fixed position a key-plate, means by which the key-plate and any of the 65

plates to be transferred to the printing plate cylinder can be made to make a series of impressions, whereby it can be determined whether the plate to be transferred is in proper registration with the key-plate, manual means for shifting each plate to be transferred until it is in register, and means for marking such plate at that time, whereby all such plates can be transferred to the printing machine and can be registered thereon by said marks in exact registration with each other for printing in colors.

10. In a machine of the character described, the combination of an impression cylinder, a proving cylinder and a marking cylinder, means for inking a plate on the proving cylinder, means for inking a plate on the marking cylinder, and means whereby sheets can be fed into the machine in such a way as to receive an imprint from a plate on the proving cylinder and an imprint on the same area from a plate on the marking cylinder, whereby the latter plate can be adjusted and further impressions made to bring it into exact registration with the plate on the proving cylinder.

11. In a machine of the character described, the combination of an impression cylinder, a proving cylinder and a marking cylinder, means for inking a plate on the proving cylinder, means for inking a plate on the marking cylinder, and means whereby sheets can be fed into the machine in such a way as to receive an imprint from a plate on the proving cylinder and an imprint on the same area from a plate on the marking cylinder, whereby the latter plate can be adjusted and further impressions made to bring it into exact registration with the plate on the proving cylinder, the proving cylinder and marking cylinder being of the same diameter and of the diameter of the printing plate on the cylinder to which the plates are to be transferred and the impression cylinder being of a diameter which is of multiple diameter.

12. In a machine of the character described, the combination of a proving cylinder, a marking cylinder and an impression cylinder located between them, said proving cylinder and marking cylinder each being adapted to support a printing plate in substantially the same condition as it would be supported on the printing plate cylinder of a press, manually operated means for moving either the proving cylinder or the marking cylinder into printing contact with the surface of the impression cylinder, and means for inking plates on the proving and marking cylinders, whereby impressions can be made from plates on both of said cylinders on a sheet carried by the impression cylinder.

13. In a machine of the character described, the combination of a proving cylinder, a marking cylinder and an impression cylinder between them, with a blanket carried on the surface of the impression cylinder, means on the impression cylinder for holding a sheet thereon, means for inking the plates on the other two cylinders, and means for moving either of the other two cylinders, or both of them, into contact with the blanket on the impression cylinder, whereby impressions can be made by both cylinders on the same sheet on the impression cylinder.

14. In a machine of the character described, the combination of a proving cylinder, a marking cylinder and an impression cylinder located between them, means for moving either or both of the first-named cylinders into contact with the effective surface of the impression cylinder, and means for rotating all three cylinders from the same source of power.

15. In a machine of the character described, the combination of an impression cylinder located in fixed bearings, a proving cylinder on one side of it and a marking cylinder on the other side, the proving cylinder and marking cylinder being mounted in eccentric bearings, and means for moving each of the last two named cylinders by their eccentric bearings into printing contact with the impression cylinder, for the purpose described.

16. In a machine of the character described, the combination of a proving cylinder and a marking cylinder, each of the same size and each of a size adapted to receive on half its circumference the printing plate to be used on a printing machine, a pair of pins located in fixed position on the proving cylinder to receive between them a printing plate previously provided with notches for engaging said pins, whereby the pins fix the position of the plate, means for clamping the plate on said cylinder, the marking cylinder having means by which the plate can be shifted longitudinally and circumferentially to bring it into perfect registration with the plate on the proving cylinder, and means for providing notches in the edges of the plates on the marking cylinder, whereby all such plates registered thereon will be adapted to be transferred to the printing cylinders on another machine in exactly the same position in each case so that they will print on the web in exact registration with each other.

17. A machine of the character described, the combination of an impression cylinder located in fixed bearings, a proving cylinder on one side of it and a marking cylinder on the other side, the proving cylinder and marking cylinder being mounted in eccentric bearings, means for moving each of the last two named cylinders by their eccentric bearings into printing contact with the impression cylinder for the purpose described, an inking mechanism for the proving cylinder, an inking mechanism for the marking cylinder, each inking mechanism comprising a form roll movably mounted, and means for moving said form rolls independently into and out of contact with their respective cylinders.

18. In a machine of the character described, the combination of a proving cylinder, a marking cylinder and an impression cylinder located between them, means for moving either or both of the first-named cylinders into contact with the effective surface of the impression cylinder, means for rotating all three cylinders from the same source of power, an inking mechanism for a plate on the proving cylinder, and a plurality of inking mechanisms for plates on the marking cylinder, each of said inking mechanisms comprising a form roll movable into and out of contact with the plates on their respective cylinders and manually operable means for moving each form roll independently toward and from its cylinder comprising means for holding the form roll away from it when moved to that position.

19. In a machine of the character described, the combination of a cylinder adapted to carry a printing plate and an impression cylinder, of an inking mechanism for the printing plate comprising a form roll, means for supporting said form roll to swing about an axis toward and from its cylinder, a spring for forcing the form roll toward the plate on the cylinder, a treadle connected for turning the form roll back and into such position that the spring cannot move the form roll toward the cylinder.

20. In a machine of the character described,

the combination of a cylinder adapted to carry a printing plate and an impression cylinder, of an inking mechanism for the printing plate comprising a fountain, a fountain roll, pick-up roll and 5 form roll, means for supporting said form roll to swing about an axis toward and from its cylinder, a link pivoted to the form roll supporting means, a spring for forcing said link in a direction to apply the form roll to the plate on the cylinder, 10 an eccentric connected with said link, a treadle connected with the eccentric for turning it to pull the form roll back and into such position that when it is pulled back it will be at dead center and the spring cannot move the form roll toward the cylinder.

21. In a cylinder for use in registering printing plates before they are placed on the plate cylinders of the printing press, the combination of means on the cylinder for moving the plates 20 circumferentially with respect to the cylinder, and means on the cylinder for moving the plates longitudinally for registering purposes.

22. In a cylinder for registering printing plates, the combination of a pair of plate-holding levers, 25 engaging the opposite straight edges of a semi-cylindrical printing plate on the cylinder, and means for simultaneously moving said levers to shift the plate circumferentially on the cylinder for registering purposes.

30 23. In a cylinder for registering printing plates before they are applied to their printing cylinder, the combination of a pair of levers for engaging the straight edges of the plates, both of said levers being pivoted, and a bar connected 35 with said levers by which both levers can be turned in a direction to shift the printing plate one way or the other around the cylinder.

24. In a cylinder for registering printing plates before they are applied to their printing cylinder, 40 the combination of a pair of levers for engaging the straight edges of the plates, both of said levers being pivoted, a bar connected with said levers by which both levers can be turned in a direction to shift the printing plate one way or the other 45 around the cylinder, said bar having a notch, and a spring adapted to engage in said notch for providing a means for normally holding the levers in substantially central position.

25. In a cylinder for registering printing plates before they are applied to their printing cylinder, 50 the combination of a pair of levers for engaging the straight edges of the plates, both of said levers being pivoted, a bar connected with said levers by which both levers can be turned in a direction to shift the printing plate one way or the other around the cylinder, said bar having a 55 rack thereon, a gear meshing with the rack, and means for turning the gear to shift the rack and bar.

60 26. In a cylinder for use in registering printing plates, the combination of means for shifting the plates longitudinally, means for shifting the plates circumferentially, and means for marking the edges of the plates when the plates are finally secured in the desired position.

27. In a cylinder for use in registering printing plates, the combination of means for shifting the plates longitudinally, means for shifting the plates circumferentially, and means whereby 70 when the plates are finally secured in the desired position their edges can be marked, said means comprising marking or notching chisels carried within the cylinder and adapted to be projected against or through the beveled curved edges of 75 the plate, a shaft in the cylinder, means on the

shaft for moving said chisels radially, and means whereby as the cylinder turns, said shaft will be turned to project the chisels.

28. The combination with a cylinder for registering printing plates, a cam movable along 5 the shaft of said cylinder, means for normally holding the cam retracted, means for projecting the cam, a shaft carried by the cylinder having an arm provided with a roller in position to be engaged by said cam once during each rotation 10 of the cylinder when the cam is projected, whereby the shaft will be oscillated, and notching chisels carried by said shaft and adapted to be projected through the curved beveled edges of a plate held on the cylinder when the cam turns 15 said shafts.

29. In a cylinder for registering printing plates, the combination of means for holding the straight edges of the plates and a pair of clamps for holding the curved edges of the 20 plates, positive means for moving one of said clamps, yielding means pressing on the other clamp so as to hold the plate against the first-named clamp, and hand-operated means for withdrawing the spring-pressed clamp to free 25 the plate.

30. In a cylinder for registering printing plates, the combination of a pair of shafts on the cylinder, a cutter projecting from each shaft for the purpose of making a notch in the edge 30 of the plate, a gear segment on each shaft, a reciprocable bar on the plate having two racks thereon, one meshing with the segment on one side and a gear meshing with the segment on the other side and also with the other rack on the 35 bar.

31. The method of registering curved printing plates on a plate cylinder, which consists in providing the plates by comparison of their respective imprints, placing the plates successively on the 40 cylinder with locating provisions on the plates registering with fixed locating provisions on the cylinder so as to locate said plates accurately in the same place on the cylinder.

32. A method of registering curved printing 45 plates to be used on the plate cylinder of a printing press which comprises preliminary mounting of the plate on a preregistering marking cylinder, shifting the plate to be registered until it registers with an impression previously made, notch- 50 ing the plate, rigidly locating the plate by cooperation of said notches with fixed locating provisions on the plate cylinder of the printing press, and clamping the curved edges of the plate.

33. A method of registering curved printing 55 plates to be used on the plate cylinder of a printing press which comprises preliminary mounting of the plate on a preregistering cylinder, shifting the plate to be registered until it registers with preset registering means, machining the 60 plate to provide locating surfaces, locating the plate on the printing cylinder by means of these machined surfaces, and clamping the curved edges of the plate.

34. The method of registering curved print- 65 ing plates, for the purpose described, which consists in preregistering a plate by shifting it on a surface until it registers with preset registering means, machining the plate to form registering surfaces, locating the plate, by means of said 70 registering surfaces, in a predetermined position on a printing cylinder, and clamping the curved edges of the plate to said printing cylinder.
